LOUIS V. ARONSON, OF NEWARK, NEW JERSEY, ASSIGNOR TO ART METAL WORKS, INC.,
A CORPORATION OF NEW JERSEY

COMBINED SAFETY RAZOR AND SHARPENING DEVICE

Application filed June 4, 1931. Serial No. 541,977.

This invention relates to improvements in combined safety razors and sharpening devices.

Among the objects of this invention is improved means for supporting a sharpening device in either of two positions on opposite faces of the edge of a safety razor blade in cooperative relation therewith, and improved means facilitating moving said sharpening device and razor blade relatively from one cooperative position to the other.

Another object of this invention is the provision of a combination of means for facilitating the sharpening of either edge of a double edged safety razor blade.

Still another object of the invention is an improved sharpening roller.

Other objects will be apparent from the following description taken in connection with the drawing, in which

Fig. 1 is a side view of a combined safety razor and sharpening device;

Fig. 2 is a view similar to Fig. 1 showing the razor head and sharpening device and carriage therefor in transverse section;

Fig. 3 is a transverse section of the razor head, sharpening device and carriage therefor showing the sharpening device in cooperative relation with the lower face of an edge of the razor blade;

Fig. 4 is a view similar to Fig. 3 showing the sharpening device and carriage moved to the right during the operation of moving the sharpening device from one face of the edge of the blade to the other face;

Fig. 5 is a view similar to Fig. 3 showing the sharpening device in cooperative relation with the upper face of the edge of the blade;

Fig. 6 is a central longitudinal section of the razor head and carriage;

Fig. 7 is a section on the line 7-7 of Fig. 2; and

Fig. 8 is a perspective view of an improved form of sharpening device.

The safety razor may include a handle 10 of any preferred form which is secured to a hollow stem 11 integral with a guard member 12 which at one of its side edges carries guard fingers 13 of any suitable preferred form.

The outer face of the guard member 12 is preferably flat to form a seat for the razor blade 14 which is preferably clamped between a shoulder 15 on a screw threaded stud 16 on an outer clamping cap 17 and the outer end of an enlarged portion 18 on a rod 19 slidable in the hollow stem 11 and normally spring-pressed by a spring 20 seated on an interior shoulder on the stem 11 and against a shoulder on a manipulative portion 21 secured to the rod 19 by a rivet or the like, as shown. The enlarged portion 18 is screw threaded interiorly to cooperate with the reduced threaded end of the stud 16 on the cap member 17 by means of which the razor blade 14 may be clamped between the shoulder 15 on the clamping cap 17 and the end of the enlarged portion 18 of the rod 19 by a clockwise turning movement of the manipulative member 21 and rod 19. Likewise, the blade 14 may be removed from the clamping cap and rod 19 by turning the manipulative means 21 counterclockwise. The side edges of the clamping cap hold the edges of the razor blade against the face of the guard member in the usual manner.

By means of the construction described, the razor blade 14 will be held in position on the guard member 12 but may be raised away from the guard member 12 by pressure on the manipulative member 21 for the purpose of disengaging alining studs 22 on the clamping cap 17 from alining holes 23 in the guard member 12, after which the razor blade may be turned about an axis passing through the rod 19 by turning the manipulative portion 21 so as to present either edge of the blade in cooperative relation with the guard fingers, or with the sharpening device which, in the form shown, comprises a roller 24.

The roller 24 is constructed of any suitable material and may be provided with a spiral rib 25, as shown in Fig. 7, or as preferred the roller may be of the form shown in Fig. 8 in which it is designated 26, and which is provided, as shown, with spaced longitudinal extending ribs 27 which, when the blade springs into the grooves formed between the ribs when the roller is revolved,

operate to press back the rough saw-like edges of the blade by the snap action produced between the blade and the roller.

For the purpose of mounting the roller so that it may be moved into cooperative relation with either face of an edge of the razor blade, the guard member 12 is provided with downwardly extending ears 30 and 31 which are slotted, as shown, to form guide ways for studs 32 and 33 carried by flanges 34 and 35 on a carriage 36 which is provided with ears 37 and 38 in which the sharpening roller 24 or 26 is suitably journaled. The flanges 34 and 35 are preferably of the shape indicated by reference characters *a*, *b*, *c* and *d* of which the edge *b* bears against the rear face of the guard member 12 when the roller is in the position shown in Figs. 1, 2 and 3, to cooperate with the studs 32 and 33 to hold the roller in the position indicated in these figures. The sliding connection between the studs and the slots in the ears 30 and 31 permits the roller to be moved in a plane parallel with the plane of the safety razor blade as the roller is drawn toward the right. It also permits the roller to be pivoted about the studs in a direction toward the face of the edge of the razor blade as pressure is applied in that direction. The slots in the ears 30 and 31 permit the roller to be moved from the position shown in Fig. 3 to the position shown in Fig. 4 prior to its being pivoted or rocked into alignment with the position it occupies in Fig. 5, and to permit its movement into the position indicated in Fig. 5. In this position the edges *a* of the flanges 34 and 35 bear against the rear face of the guard member 12 to hold the roller substantially in the position indicated. The relation of the edges *a* to the studs 32 and 33 is such as to permit the roller to be pressed against the upper face of the edge of the razor blade as pressure is applied during the operation of sharpening.

The carriage 36 may also be provided with flanges 39 and 40 which are of the general shape of the flanges 34 and 35 as indicated by the reference characters *e*, *f*, *h*, *i* and *j*, of which the edges *f* and *h* function the same as the edges *a* and *b* of flanges 34 and 35. As the carriage is moved to the right, as shown in Fig. 4, the cam edges of the notch *g* in the edges *f* of the flanges 39 and 40 coact with the wedge-shaped ends of the studs 22 to raise the razor blade and clamping cap 17 into the position shown in Fig. 4. This compresses the spring 20, the reaction of which is to apply pressure on the edges *h* of the flanges 39 and 40 after the studs 32 and 33 have been moved into the position shown in Fig. 4. The result of this is to initiate the pivotal movement of the roller carriage from the position shown in Fig. 4 in an upward direction toward the position it finally assumes when in cooperative rela-

tion with the upper face of the edge of the razor blade, as shown in Fig. 5. From this position the carriage is moved to the left into the position shown in Fig. 5 in which the surfaces *f* on the flanges 39 and 40 cooperate with the lower face of the guard member 12 to hold the roller in proper cooperative relation with the blade. The upper face of the edge of the razor blade is then honed or stropped by turning the roller 24 or 26 after which the parts are manipulated so as to bring the roller into the position shown in Figs. 1, 2 and 3 which position they occupy during shaving operations.

As indicated in Figs. 1 and 3, the studs 22 prevent any appreciable movement of the carriage to the right so that the roller will remain in substantially the position shown unless it is drawn to the right. The studs also hold the roller substantially in the position shown in Fig. 5 unless force is applied to draw it to the right.

When the roller is in the position shown in Figs. 1, 2 and 3, and it is desired to reverse the position of the edges of the razor blade, pressure is applied on the manipulative portion 21 on the rod 19 to raise the razor blade until alining pins or studs 22 are free of the guard member 12, after which a rotational movement of the razor blade is effected by turning the manipulative portion 21. After this has been effected the spring 20 is permitted to draw the razor blade into the position shown in these figures.

While the invention has been described with reference to a preferred form of mounting means for the sharpening device and with reference to preferred forms of sharpening means, it is to be understood that changes may be made without departing from the spirit of the invention and the claims are not to be limited by the terms of the description therein employed only to the extent that they are limited by the prior art.

What I claim is:

1. In a combined safety razor and sharpening device, the combination of a double edged razor blade, a support therefor, a clamping plate for clamping the razor blade on said support, a yielding means for holding said clamping means with respect to said support, a sharpening device, and means connecting said sharpening device and said support facilitating a relative sliding and pivotal movement between said sharpening device and said support whereby the sharpening device may be brought into engagement with either face of an edge of the razor blade, the yielding connection between the clamping member and the support facilitating movement of the razor blade away from its support to permit rotation of the razor blade to present either edge to said sharpening device.

2. The combination of a safety razor and sharpening device comprising a razor blade

support, an outer clamping member spring-pressed toward said support, a wedge-shaped member on said clamping member, a sharpening device, means supporting said sharpening device on said support for relative sliding movement with respect to said support, and means on said supporting means cooperating with said wedge-shaped member on said clamping member for holding said sharpening device in cooperative relation with a razor blade on said support.

3. In a combined safety razor and sharpening device, the combination of a plate seat for supporting a safety razor blade, flanges extending from the rear face of said plate seat, a sharpening device, a carriage supporting said sharpening device, flanges on said carriage overlapping said flanges on said seat, and pivoting and sliding connections between 20 the flanges on said seat and the flanges on said carriage.

4. In a combined safety razor and sharpening device, the combination of a support for a safety razor blade, ears formed on said support, a sharpening device, a carriage supporting said sharpening device, flanges on said carriage, and pivoting and sliding connections between said ears and flanges, said flanges on said carriage provided with faces adapted to cooperate with the rear face of said support to guide and hold the sharpening device in the proper position with respect to the razor blade.

5. In a combined safety razor and sharpening device, the combination of a support for a safety razor blade, ears formed on said support, a sharpening device, a carriage supporting said sharpening device, flanges on said carriage, and pivoting and sliding connections between said ears and flanges, said flanges on said carriage being provided with faces adapted to cooperate with the rear face of said support to guide and hold the sharpening device in the proper position with respect to the rear face of the edge of the razor blade, said flanges being also provided with faces adapted to cooperate with the rear face of the support to hold the sharpening device in proper cooperative relation with the forward face of the edge of the safety razor blade.

6. In a combined safety razor and sharpening device, the combination of a support for a safety razor blade, slotted ears formed on the side edges of said support, a sharpening device, a carriage supporting said sharpening device, flanges on said carriage, pivot studs on said flanges operating in the slots in the ears of said support, said flanges on said carriage being provided with faces adapted to cooperate with the rear face of said support to guide and hold the sharpening device in the proper position with respect to the rear face of the edge of the razor blade, said flanges being also provided with

faces adapted to cooperate with the rear face of the support to hold the sharpening device in proper cooperative relation with the forward face of the edge of the safety razor blade, yieldingly drawn means for supporting the razor blade on said support, and means on said clamping means and said carriage for the sharpening device cooperating to move the clamping member away from the support as the sharpening device is moved laterally away from the rear face of the edge of the razor blade, said means on said clamping member initiating the pivotal movement of the carriage supporting the sharpening device toward the position it assumes before it is moved into engagement with the forward face of the edge of the razor blade.

7. In a combined safety razor and sharpening device, a plate seat for supporting a razor blade, a handle rigidly secured to said seat, a sharpening device, a carriage on which said sharpening device is supported, means for supporting said carriage on said plate seat for sliding and pivoting movements respectively parallel and transverse with respect to the plane of a blade on said seat, and guiding means for controlling said sliding movement to cause proper cooperative engagement between a razor blade on said seat and said sharpening device.

8. In a combined safety razor and sharpening device, a support for a razor blade, rearwardly extending slotted ears on said support, a sharpening device, a carriage supporting said device, studs on said carriage operating in said slots facilitating movement of said sharpening device into cooperative relation with either face of the edge of a razor blade on said support, and means limiting the pivoting movement of said carriage to restrain the sharpening device from movement beyond the positions in which it cooperates with the faces of the edge of the razor blade.

9. The combination of a razor blade supporting means, a sharpening device, a support for said sharpening means, a connection between said supporting means and said support facilitating relative sliding and pivoting movements respectively parallel and transverse with respect to the plane of a blade on said seat to permit of relatively positioning a razor blade and the sharpening device for sharpening either face of the edge of the razor blade, and yielding means for limiting the relative sliding movements and initiating a relative pivoting movement of said supporting means and said support as it limits the relative sliding movements.

In testimony whereof I have signed my name to this specification.

LOUIS V. ARONSON.
